UNITED STATES PATENT OFFICE.

JOHN JAMES ARMSTRONG, OF HONOLULU, AND ROBERT RENTON HIND, OF EWA,
TERRITORY OF HAWAII.

INTERMEDIATE APRON CONVEYER FOR SUGAR-CANE MILLS.

1,289,075.

Specification of Letters Patent. Patented Dec. 31, 1918.

Application filed December 26, 1913. Serial No. 808,797. Renewed May 18, 1918. Serial No. 235,390.

To all whom it may concern:

Be it known that we, JOHN JAMES ARMSTRONG, residing at Honolulu, and ROBERT RENTON HIND, residing at Ewa, in the county 5 of Honolulu and Territory of Hawaii, citizens of the United States, have invented certain new and useful Improvements in Intermediate Apron Conveyers for Sugar-Cane Mills; and we do hereby declare the following to be a full, clear, and exact description of the invention, such as will enable others skilled in the art to which it appertains to make and use the same.

This invention relates to apron conveyers, 15 such as are known as intermediate carriers and are used between sugar-cane mills for conveying the crushed cane from one mill and feeding it to the next mill, and particularly to the aprons or belts of such conveyers.

The apron of intermediate carriers of sugar-cane mills usually consists either of endless chains or belts with steel slats attached, or a canvas belt.

25 The steel slat apron conveyer is objectionable due to the frequent breakages which occur, either of the slats or of the links, causing considerable loss of time. Another objection is that the diluted juices or water intended for maceration which passes through the crushed cane on the apron without having fulfilled its function, that of absorbing sucrose in the crushed cane, is not retained by the apron but leaks through between the 30 slats and mixes with the mill juices, thus adding unnecessary water which has to be evaporated later on. A greater objection, however, is that the cushion-cush, or fine cane pulp, sifts through the openings between the 35 slats and adheres to the links of the chain belts and to the underside of the slats and quickly inverts or becomes sour, thereby converting a quantity of good sucrose to invert sugar. This loss always occurs so long as 40 this sour cushion-cush remains on the apron to infect the juices, and it may assume large proportions, as a slat conveyer cannot be properly cleaned while the mill is operating.

45 The canvas belt apron, while not causing trouble or delays through breakage or the sifting of cushion-cush through the apron, is not greatly superior to the slat conveyer in regard to the losses by inversion. The fabric of the canvas belt gradually absorbs the

cane juices, which sour and cause losses of a 55 serious proportion. These sour juices cannot be removed, nor can the canvas belt be properly cleaned while the mill is running.

Our invention contemplates an apron of non-corrosive sheet metal, such as phosphor 60 bronze, Muntz's metal or hard rolled copper, for example, which will overcome all of the objections above mentioned, for it will be as free from breakage as is the canvas belt, it will not absorb juices nor harbor cushion-cush, 65 and will therefore entirely eliminate the losses by inversion above mentioned, and at all times it will be absolutely clean. This apron may be made endless by brazing the ends together, or if preferred, the ends may 70 be hooked or hinged together. It may be made in one piece, or be made up of a series of suitable lengths, such that any section can be easily replaced in the event of it becoming necessary to do so. To overcome the possible objection that the crushed cane would 75 slip on this sheet metal apron and that therefore it would not properly feed the crushed cane to the mill, we provide the apron with embossments or with protuberances, as will 80 hereinafter more fully appear.

In the accompanying drawings, forming a part of this specification, Figure 1 represents in sectional elevation an intermediate carrier or apron conveyer for sugar-cane mills embodying our invention. Fig. 2 represents a half section taken on the line A—A of Fig. 1. Fig. 3 is a detail showing one method of hooking together the ends of our metallic apron. Fig. 4 represents in plan a 90 portion of our apron showing a preferred form of embossments. Fig. 5 is a section on the line B—B of Fig. 4. Fig. 6 represents a side view of a portion of our improved apron showing protuberances, and the sections 95 hinged together. Fig. 7 is a detail showing one method of constructing the protuberances.

Referring to the drawings, the apron 1, which is made of non-corrosive sheet metal, 100 such as phosphor bronze, Muntz's metal, hard rolled copper, for example, passes around the drums 2 and 3, and conveys the crushed cane discharged from the mill C and feeds it to the mill D. The drum 2 is revolved, and the drum 3 is provided with take-ups, in the same manner as is usual with canvas belt aprons. The weight of the

crushed cane in transit is supported by the apron 1 sliding upon the I beams or supports 4. The apron 1 may be made endless by brazing, or it may be made in one or 5 more sections suitably joined. For example, the ends may be hooked together as shown in Fig. 3, or they may be hinged together as shown in Fig. 6. To prevent the 10 possibility of the crushed cane slipping on the apron 1, and to insure proper feeding to the mill D, the apron 1 may be provided with embossments 1^a, or with protuberances 1^b, or the like. A preferred form of embossments 1^a is shown in Figs. 4 and 5. One 15 form of protuberances 1^b is illustrated in Fig. 7, but they could be brazed onto the apron 1 if preferred.

We claim:

An intermediate apron conveyer for sugar-cane mills, comprising an inclined endless 20 belt of non-corrosive and imperforate sheet-metal, said belt being of sufficient width to convey the sugar-cane from one mill to another and having protuberances embossed thereon to prevent slippage of the sugar- 25 cane.

In testimony whereof we affix our signatures, in presence of two witnesses.

JOHN JAMES ARMSTRONG.
ROBERT RENTON HIND.
